ATTORNEY

UNITED STATES PATENT OFFICE

145,142

DESIGN FOR A TOY FERRY BOAT

George N. Overath, Belleville, N. J., assignor to
Engineers, Incorporated, Irvington, N. J.

Application May 23, 1945, Serial No. 119,685

Term of patent 3½ years

(Cl. D34—15)

To all whom it may concern:

Be it known that I, George N. Overath, a citizen of the United States of America, residing at Belleville, in the county of Essex and State of New Jersey, have invented a new, original, and ornamental Design for a Toy Ferry Boat, of which the following is a specification, reference being had to the accompanying drawing, forming part thereof.

In the drawing:

Figure 1 is a side elevation of a toy ferry boat showing my new design.

Figure 2 is a top plan view thereof.

Figure 3 is an end view of a toy ferry boat showing my new design.

I claim:

The ornamental design for a toy ferry boat, as shown.

GEORGE N. OVERATH.
